(57) **CLAIM**

The ornamental design for a liquid dispenser, as shown and described.

DESCRIPTION

FIG. 1 is a perspective view of a liquid dispenser showing my new design placed in a stand.

FIG. 2 is a top plan view thereof.

FIG. 3 is a front elevation view thereof.

FIG. 4 is a side elevation view thereof.

FIG. 5 is a side elevation view of a liquid dispenser removed from the stand.

FIG. 6 is a bottom plan view of the liquid dispenser; and,

FIG. 7 is a front elevation view of the liquid dispenser as shown in FIG. 5.

The broken lines in the figures are for illustrative purposes only and form no part of the claimed design.
